HOLLOW-POINT BULLET.

1,095,501.

Specification of Letters Patent.

Patented May 5, 1914.

Application filed February 24, 1914. Serial No. 820,618.

To all whom it may concern:

Be it known that I, FRANK O. HOAGLAND, a citizen of the United States, residing at Bridgeport, county of Fairfield, State of Connecticut, have invented an Improvement in Hollow-Point Bullets, (Case B,) of which the following is a specification.

This invention relates to the class of bullets illustrated and described in patent to 10 T. C. Smith, No. 549,334, dated Nov. 5, 1895, and has for its object to provide a bullet of this type which will mushroom more completely and which will moreover be especially adapted for use as an illuminating 15 bullet, that is, a bullet that upon impact will produce a flash of light or a puff of smoke, or both, to show if it strikes a target, and where, and in other uses to show where the bullet strikes relatively to the 20 objective and if the rifle sights require adjustment for distance.

With these and other objects in view I have devised the novel bullet which I will now describe, referring to the accompanying 25 drawing forming a part of this specification and using reference characters to indicate the several parts.

Figure 1 is a sectional view illustrating a form of slug for my novel bullet; Fig. 2 30 an elevation of the completed bullet with a closed tip; Fig. 3 a section on the line 3—3 in Fig. 2, looking in the direction of the arrows, showing fulminate within the central recess; Fig. 4 a longitudinal section of 35 a completed bullet without fulminate, but with an open tip; Fig. 5 a view illustrating the first effect upon the bullet of impact with an objective; Fig. 6 a view showing the bullet completely mushroomed when not 40 used as an illuminating bullet, and Fig. 7 is a similar view showing the effect of impact with a target upon the bullet when prepared as an illuminating bullet, the mushroomed forward end having been 45 blown off by the detonation of the fulminating compound within the recess.

The slug for my novel bullet is formed substantially as in Fig. 1, a cup-shaped recess being formed in the forward end of 50 the slug which is surrounded with a wall 10. It will of course be understood that the exact configuration of the recess is not of the essence of the invention. I preferably however, as shown in the drawing, form the

outer side of the wall of the slug parallel 55 with the axis thereof, and the wall surrounding the recess of diminishing thickness from the base of the recess outward. The bullet is completed by swaging the forward end thereof to the desired tapering 60 form by means of a corrugated die, the effect of which is to produce in the completed bullet a series of alternate longitudinal ribs 11 and depressions 12, which converge toward the tip, as clearly shown. The tip of 65 the bullet may be entirely closed or, if preferred, an opening 13 may be left leading from the tip into the central recess, indicated by 14. This recess may of course be made of any required size, depending upon 70 the special use for which the bullet is intended. I find in practice that the alternate longitudinal grooves and depressions converging toward the tip assist greatly in the mushrooming of the bullet without regard to whether an opening is or is not left leading in to the central recess. When intended to be used as an illuminating bullet the central recess is partly or wholly 75 filled with a suitable flashing compound, indicated by 15. The special flashing compound used is not of the essence of the invention, it being simply required to use any suitable compound that will ignite upon impact with a target or other objective and produce a flash of light, or a puff of smoke, or both.

The first effect of impact upon a bullet is indicated in Fig. 5. The resistance of the target or other objective to the forward 90 movement of the bullet causes the hollow forward end thereof to flatten out, as indicated. If no flashing compound is used, an instant later the bullet will assume substantially the form illustrated in Fig. 6. 95 If a flashing compound is used, the ignition thereof will ordinarily blow off the forward end of the bullet, as indicated in Fig. 7.

Having thus described my invention I claim:

1. A bullet of the character described having a recess in its forward end, the tapering forward end of the bullet being formed by swaging the metal into alternate ribs and depressions which converge toward the tip. 105
2. A bullet of the character described formed from a slug having a cup-shaped

recess in its forward end, the wall of the recess forming the tapering portion of the completed bullet and being closed inward to form alternate ribs and depressions which converge toward the tip.

3. A bullet of the character described having a recess in its forward end, and an opening leading from the tip into said recess, the tapering portion of the bullet being formed by closing the metal inward in the form of alternate ribs and depressions which converge toward the tip.

4. A bullet of the character described hav-

ing a recess in its forward end and a flas-
ting compound in said recess, for the purpose 15
set forth, the tapering portion of the bullet
being formed by closing the metal inward
in the form of alternate ribs and depressions
which converge toward the tip.

In testimony whereof I affix my signa- 20
ture in presence of two witnesses.

FRANK O. HOAGLAND.
